UNITED STATES PATENT OFFICE.

GEORGE McELWAIN, OF EL PASO, TEXAS.

ORE-SEPARATING APPARATUS.

1,299,848.

Specification of Letters Patent.

Patented Apr. 8, 1919.

Application filed November 12, 1917. Serial No. 201,582.

To all whom it may concern:

Be it known that I, GEORGE McELWAIN, a citizen of the United States, residing at El Paso, in the county of El Paso, in the State of Texas, have invented certain new and useful Improvements in an Ore-Separating Apparatus; and I do hereby declare the following to be a full, clear, and exact description of the same, reference being had 10 to the accompanying drawings, forming part of this specification.

This invention relates to apparatus adapted to separate pulverized ore into its constituents and, as a large percentage of valuable ores is found in those portions of the country where water is not readily available, one of the objects of the present invention is to provide a machine which will separate the ore while in a dry condition, thus 20 rendering the use of water unnecessary.

Another object is to provide a machine that is simple in design and consequently cheap to manufacture and will separate the ores quickly and thoroughly.

With these and other objects in view as will appear from the following description, the invention consists in certain novel details of construction, combinations and arrangements of parts, all as will be herein 30 described and particularly pointed out in the claims at the end of the specification.

In the accompanying drawings in which the present invention is shown in the preferred form;

Figure 1 is a side elevation, a portion of the casing being broken away, showing the interior construction of the machine.

Fig. 2 is a transverse sectional view taken on the line 2—2 of Fig. 1 in the direction 40 of the arrows;

Fig. 3 is a side elevation of a modified form of receptacle, and

Fig. 4 is a modified form of receptacle for receiving the heavier ores separated 45 from the gage and means for agitating the ore accumulated therein.

Like letters of reference in the several figures indicate the same parts.

Referring particularly to Figs. 1 and 2, 50 reference numeral 1 indicates the standards of a suitably constructed frame work on which is mounted a hollow casing 2, preferably of cylindrical cross section, forming a duct through which the ore is conveyed to 55 be separated by means to be presently described. Adjacent one end of casing 2 is

mounted a hopper 3 adapted to deliver the ore, which has previously been pulverized by any suitable method, to casing 2. Casing 2, adjacent the end opposite to that on which the hopper 3 is mounted, is provided in its bottom with a discharge opening 4 for the tailings and intermediate the discharge opening 4 and the hopper 3 the bottom of casing 2 is cut away, as shown at 5^a in Fig. 60 1, to form an elongated opening 5 through which the relatively heavy ores or "values" are discharged into a receptacle 6 which is rigidly secured to the edge of the casing adjacent the opening 5 by any suitable fastening devices, and forms a chamber below said opening. Receptacle 6 is provided in its bottom with a plurality of discharge outlets 7, each normally closed by a gate 8. One end of each gate is pivotally secured to 75 the receptacle 6 at 9 and its other end, which forms a handle 10, seats in a recessed projection 11 on the receptacle, to properly center the gate over the discharge opening. To withdraw the separated ores, the gate 8 is 80 raised by its handle 10 and, when released, the gate will return to its closed position by its own weight.

The preferred means for conveying the body of ore through the casing or duct 2 85 and separating it into its constituents will now be described. Extending longitudinally of casing 2 and journaled in heads 12, of any suitable material, which close the ends of casing 2, is a shaft 13, adapted to be 90 rotated by hand wheel 14 or a gear wheel 15 driven by power derived from any suitable source. Rigidly mounted on shaft 13 and spaced radially therefrom by means of rods or braces 16 is a plurality of conveyer blades 95 17 of approximately the same diameter as the interior of the casing and preferably of helical form, adapted to simultaneously agitate the ore and convey it through the casing or duct 2. The several conveyer blades 17 100 are spaced apart longitudinally of the shaft 13 and intermediate each pair of conveyer blades a plurality of substantially straight beater blades 18, is mounted on shaft 13 at approximately right angles thereto. These 105 beaters agitate the body of ore and the combined action of conveyers 17 and beaters 18 so thoroughly agitates the mass that the valuable ore particles, being relatively heavy compared with the weight of the individual 110 particles of waste substances gradually settle downwardly, or gravitate toward the bot-

tom of the casing while progressing through the casing and the lighter particles are displaced upwardly toward the top of the body of ore, thus irregularly stratifying the entire mass. The heavier ore particles when they reach the lower portion of the mass of ore will descend by gravity, through the discharge opening 5 and pass downwardly into receptacle 6 while the lighter waste particles of tailings which form the upper strata of the mass, are conveyed by the blades 17 to the extreme end of the casing 2 where they are discharged through the tailings discharge opening 4. The heavier ore particles which may be on the top of the mass of ore, when the latter is introduced into the casing 2, will, of course, consume a longer period of time in reaching the bottom and it is to prevent the loss of these particles that the discharge opening 5 and the receptacle are extended throughout practically the entire length of the casing, it being understood, of course, that the length of the discharge opening is dependent upon the character of the ore to be separated and the speed of its progress with relation to the degree of agitation.

To increase the capacity of the machine, the casing 2 is provided with means adapted 30 to retard the progress through the casing of the bottom portion of the mass of ore and permit the heavy particles to more readily descend through the discharge opening 5. The means for accomplishing this result 35 preferably consists of a plurality of curved bars 19, bridged across the discharge opening and secured to the casing by any suitable form of fastening devices. These bars 19 are of substantially the same contour as the 40 wall of the casing 2 and are adapted to engage the heavier ore particles in the bottom portion of the mass and retard their progress through the casing, the ore particles, when thus partially freed from the forces 45 exerted upon them by the conveyer blades, being more susceptible to the forces of gravity and consequently descend from the casing into the receptacle 6 more quickly.

Journalized in the ends of the receptacle 6 50 is a second shaft 20 on which is mounted a plurality of beaters 21 of such length as to pass beneath the conveyers 17 and beaters 18 in casing 2. Shaft 20 is rotated by a gear wheel 22 mounted on the end thereof and 55 adapted to mesh with gear wheel 15 on shaft 13. Beaters 21 agitate and stratify the ore particles accumulated on the receptacle 6 so that should any sand or other waste substances reach the receptacle it will be held 60 in the upper portion of the receptacle, the heavier ore particles gravitating or settling toward the outlets 7 from which they may be readily withdrawn.

In the construction shown in Fig. 3 the 65 outlets 7 of receptacle 6 are closed by caps

30 removably secured to depending flanges 31 in receptacle 6 by a screw thread connection and to prevent the material accumulated in the receptacle from dropping out when the caps are removed, there is provided 70 a series of cut-offs 32, one cut-off for each cap, rigidly mounted on shafts 33 journaled in the sides of receptacle 6. Each cut-off 32 is normally held in open position, as shown, but when it is desired to remove any 75 one of the caps 30 the corresponding cut-off is turned to its closed position as shown in dotted lines by means of a handle 34 mounted on the end of shaft 33 projecting from the side of the receptacle. In the 80 modification shown in Fig. 4, the casing 2 is provided with a plurality of small discharge openings 40 for the heavy ores which are held in receptacles 41 secured to the casing below each opening 40. A vertically 85 extending shaft 42 to which a plurality of beater blades or agitators 43 is secured is mounted in each receptacle 41 and for rotating these shafts, they are provided at their lower ends, which project from the bottoms of the receptacles, with a gear wheel 44 meshing with gear wheel 45 on a rotatable shaft 46, the latter being driven by any suitable means. These agitators cause a 90 stratification of the ore particles accumulated in the pockets, in the same manner as the body of ore is stratified in casing 2, so that should any sand, or other waste substances, reach the receptacles, it will be held in the upper portion of the receptacles, the 95 heavier ore particles settling in the bottom of the receptacles from which they may be withdrawn through outlets 47.

What I claim is:

1. In a machine for separating ore into its 105 constituents in a dry condition, the combination of an elongated casing forming a duct for the ore and having a discharge opening for tailings at one end and a discharge opening in its lower portion intermediate the ends for the relatively heavy ores, a hopper for delivering the ore to said casing, and mechanical means for conveying the ore through said casing and simultaneously agitating and effecting gravity stratification thereof during such movement, the heavier ore particles settling downwardly through the body of the ore toward the bottom of the casing and finally passing downwardly through said discharge opening, and 120 the lighter particles passing away through the end discharge opening.

2. In a machine for separating ore into its constituents in a dry condition, the combination of an elongated casing forming a 125 duct for the ore and having a discharge opening for tailings at one end and a discharge opening in its lower portion for the relatively heavy ores, a delivery hopper, mechanical means for conveying the ore through 130

- 5 said casing and simultaneously effecting stratification thereof during such movement, the heavier ore particles settling downwardly through the body of ore toward the bottom of the casing and finally passing downwardly through said discharge opening, and means for retarding the progress through the casing of the ore particles in the lower portion of but above the bottom of the body of the ore whereby their stratification 10 for passage through the respective discharge openings is augmented.
3. In a machine for separating ore into its constituents in a dry condition, the combination of an elongated casing forming a duct for the ore and having a discharge opening for tailings at one end and a discharge opening in its lower portion for the relatively heavy ores, a hopper for the relatively heavy ores, a hopper for delivering ore to the casing, a shaft journaled in said casing, means for rotating said shaft, a plurality of conveyer blades and a plurality of beaters mounted on said shaft for conveying the ore through the casing and simultaneously effecting stratification thereof during such movement, the heavier ore particles settling downwardly through the body of the ore and finally passing downwardly through the discharge opening, and means mounted in the bottom of the casing and above the bottom of the body of ore for retarding the progress of the ore particles in the lower portion of the body of ore through the casing, whereby their passage through the discharge opening is augmented.
4. In a machine for separating ore into its constituents in a dry condition, the combination of an elongated casing forming a duct for the ore and having a tailings discharge at one end and a longitudinally extending elongated discharge opening in its lower portion for the relatively heavy ores, a hopper for delivering ore to said casing, an ore receptacle below the elongated discharge opening, mechanical means for conveying the ore through said casing and simultaneously effecting stratification thereof during such movement, the heavier ore particles settling downwardly through the body of ore toward the bottom of the casing and finally passing downwardly through the discharge opening into said receptacle and means for retarding the progress through the casing of the ore particles in the lower portion of but above the bottom of the mass of ore whereby the passage of the heavier particles through the discharge opening is augmented.
5. In a machine for separating ore into its constituents in a dry condition, the combination with an elongated casing forming a duct for the ore and provided with a longitudinally extending elongated discharge opening in its lower portion for the relatively heavy ores, an ore receptacle below the discharge opening provided with a plurality of outlets, said outlets being spaced longitudinally of the receptacle, closures for said outlets and mechanical means for conveying the ore through said casing and simultaneously effecting stratification thereof during such movement, the heavier ores settling downwardly through the body of ore toward the bottom of the casing and finally passing downwardly through said discharge opening into said ore receptacle.
6. In a machine for separating ore into its constituents in a dry condition, the combination with an elongated casing forming a duct for the ore and provided with a longitudinally extending opening in its lower portion for the relatively heavy ores, an ore receptacle below the discharge opening provided with a plurality of outlets, said outlets being spaced longitudinally of the receptacle, mechanical means for conveying the ore through said casing and simultaneously effecting stratification thereof during such movement, the heavier ores settling downwardly through the body of ore toward the bottom of the casing and finally passing downwardly through said discharge opening into said ore receptacle, means for retarding the progress through the casing of the ore particles of the lower strata, but above the bottom of the ore body whereby their passage through the discharge opening into the pockets is augmented.
7. In a machine for separating ore into its constituents in a dry condition, the combination of an elongated casing forming a duct for the ore and having an elongated discharge opening in its lower portion for the relatively heavy ores, a hopper for delivering ore to the casing, an elongated ore receptacle below said discharge opening provided with a plurality of outlets, a shaft journaled in said casing, means for rotating said shaft, a plurality of conveyer blades and beaters mounted on said shaft for conveying the body of ore through the casing and simultaneously effecting stratification thereof during such movement, the heavier ore particles settling downwardly through the body of ore and forming the lower strata and finally passing through the discharge opening into said ore receptacle, and means mounted in the bottom of the casing and above the ore receptacle for retarding the progress of the bottom strata of ore particles through the casing whereby their passage through the discharge receptacle opening into said receptacle is augmented.
8. In a machine for separating ore into its constituents in a dry condition, the combination with an elongated casing forming a duct for the ore, said casing having an elongated discharge opening in its lower portion for the relatively heavy ores and a discharge opening at one end for the tailings, a deliv-

ery hopper at the other end of the casing for delivery of ore to said casing, mechanical means for conveying the ore through the casing and simultaneously effecting stratification thereof during such movement, the heavier ore particles settling downwardly through the body of the ore toward the bottom of the casing and forming the lower stratum and finally passing downwardly through said discharge opening, the lighter particles or tailings forming the upper strata being carried to and discharged through the tailings discharge opening, and means for retarding the progress through the casing of the ore particles in the lower stratum and above the bottom of the body of ore whereby their passage through the discharge opening in the bottom of the casing is augmented.

9. In a machine for separating ore into its constituents in a dry condition, the combination of an elongated cylindrical casing forming a duct for the ore and having a delivery hopper mounted on said casing, a shaft rotatably mounted in and extending longitudinally of the casing, means for rotating said shaft, a plurality of conveyer blades mounted on said shaft and spaced radially therefrom and a plurality of beaters mounted on said shaft, intermediate the conveyer blades, said conveyer blades and beaters being adapted to convey the mass of ore through the casing and simultaneously effect stratification thereof during such movement, the heavier ore particles gravitating downwardly through the mass of ore and finally passing through the discharge opening.

10. In a machine for separating ore into its constituents in a dry condition the combination of an elongated hollow casing forming a duct for the ore, a hopper for delivering the ore to said casing, an elongated receptacle for the heavy ores positioned below the casing and communicating with the interior thereof, mechanical means for conveying the ore through the casing and simultaneously effecting stratification thereof, during such movement, the heavier ore particles settling downwardly through the mass of ore toward the bottom of the casing and finally passing out of the casing into the receptacle, and means for retarding the progress through the casing of the heavier ore particles in the lower portion of the mass of ore, and above the bottom thereof whereby the passage of the heavier ore particles into the receptacle is augmented.

11. In a machine for separating ore into its constituents in a dry condition the combination of an elongated hollow casing forming a duct for the ore and having a discharge opening for the relatively heavy ores in its bottom portion, an ore receptacle below said discharge opening, a hopper mounted on the casing, a shaft mounted in said casing, means for rotating said shaft, a

plurality of conveyer blades mounted on said shaft and spaced radially therefrom and a plurality of beaters mounted on said shaft, said conveyer blades and beaters being adapted to convey the mass of ore through the casing and simultaneously effect stratification thereof during such movement, the heavier ore particles settling downwardly through the mass of ore toward the bottom of the casing and finally passing downwardly through the discharge opening into said receptacle, and mechanical means in said receptacle for effecting stratification of the ore particles accumulated in the receptacle, whereby the lighter particles pass back into the casing and the heavier particles pass to the bottom of the receptacle.

12. In a machine for separating ore into its constituents in a dry condition, the combination of an elongated casing forming a duct for the ore and having a discharge opening in its bottom for the relatively heavy ores, a hopper for delivering ore to the casing, a receptacle below the discharge opening, mechanical means for conveying the ore through the casing and simultaneously effecting stratification thereof during such movement, the heavier ore particles settling downwardly through the body of ore and passing through the discharge opening into said receptacle, and mechanical means for effecting stratification of the ore particles accumulated in the receptacle, whereby the lighter particles pass back into the casing and the heavier particles pass to the bottom of the receptacle.

13. In a machine for separating ore into its constituents in a dry condition, the combination of a hollow casing forming a duct for the ore and having a discharge opening in its bottom portion for the relatively heavy ores, a delivery hopper, an ore receptacle positioned below said discharge opening, a shaft mounted in said casing, means for rotating said shaft, a plurality of conveyer blades and a plurality of beaters mounted on said shaft for conveying the mass of ore through the casing and effecting stratification thereof during such movement, the heavy ore particles settling toward the bottom of the mass of ore and passing through the discharge opening into the receptacle, a shaft mounted in the receptacle adapted to be rotated by the rotating means of the first mentioned shaft and a plurality of beaters mounted on said shaft adapted to effect stratification of the ore particles accumulated in the receptacle.

14. In an apparatus for separating ore into its constituents in a dry condition, the combination of a hollow casing forming a duct for the ore, an ore receptacle below the casing and communicating with the interior thereof, mechanical means for conveying the ore through the casing and effecting stratification of the ore particles accumulated in the receptacle.

- fication thereof during such movement, the heavier ore particles settling downwardly through the mass of ore and passing from the casing into said receptacle, a shaft 5 mounted in said receptacle, means for rotating said shaft, and a plurality of beaters mounted on said shaft adapted to agitate the ore particles in said receptacle and effect stratification thereof, whereby the heavier 10 particles move to the bottom of the receptacle and the lighter particles move up into the casing.
15. In a machine for separating ore into its constituents in a dry condition, the combination of an elongated casing forming a duct for the ore and having a discharge opening in its lower portion for the relatively heavy ores, a hopper for delivering ore to said casing, an ore receptacle positioned below said discharge opening, a shaft journaled in said casing, means for rotating said shaft, a plurality of conveyer blades mounted on said shaft and spaced radially therefrom, and a plurality of beaters mounted 20 on said shaft, said conveyer blades and beaters being adapted to convey the ore through the casing and simultaneously effect stratification of the ore during such movement, the heavy ore particles settling 25 downwardly through the body of ore and passing through the discharge opening, and means for mechanically stratifying ore particles accumulated in the receptacle and to return the lighter particles to the casing.
- 30 16. In a machine for separating ore into its constituents in a dry condition, the combination of an elongated casing forming a duct for the ore and having a discharge opening in its lower portion for the relatively heavy ores, a hopper for delivering ore to said casing, an ore receptacle positioned below said discharge opening, a shaft journaled in said casing, means for rotating said shaft, a plurality of conveyer blades 35 mounted on said shaft and spaced radially therefrom, and a plurality of beaters mounted on said shaft, said conveyer blades and beaters being adapted to convey the ore through the casing and simultaneously effect stratification of the ore during such movement, the heavy ore particles settling 40 downwardly through the body of ore and passing through the discharge opening, a shaft mounted in said receptacle adapted to be rotated by the rotating means of the first 45
- 50 17. In a machine for separating ore into its constituents in a dry condition, the combination of an elongated casing forming a duct for the ore and having a discharge opening in its lower portion for the relatively heavy ores, a hopper for delivering ore to the casing, an ore receptacle positioned below the discharge opening, and mechanical means for conveying the ore through said casing and simultaneously effecting stratification thereof, the heavier ore particles settling 55 downwardly through the body of ore to the bottom of the casing and passing through said discharge opening into the receptacle, means mounted in the bottom of the casing above the bottom of the body of ore for retarding the progress through the casing of the ore particles in the lower portion of the mass of ore, whereby their passage through the discharge opening into the receptacle is augmented, and means mounted in the receptacle for mechanically effecting stratification of the ore particles accumulated in the receptacle.
- 60 18. In a machine for separating ore into its constituents in a dry condition, the combination of an elongated casing forming a duct for the ore and having a discharge opening in its lower portion for the relatively heavy ores, a hopper for delivering ore to the casing, an ore receptacle positioned below the discharge opening, mechanical means for conveying the ore through said casing and simultaneously effecting stratification thereof, the heavier ore particles settling 65 downwardly through the body of ore to the bottom of the casing and passing through said discharge opening into the receptacle, means mounted in the bottom of the casing above the receptacle for retarding the progress through the casing of the ore particles in the lower portion of the mass of ore, whereby their passage through the discharge opening into the receptacle is augmented, and means mounted in the receptacle for mechanically effecting stratification of the ore particles accumulated in the receptacle.
